UNITED STATES PATENT OFFICE.

MARK SPRENKLE, OF BRIDGETON, NEW JERSEY.

BEVEL SQUARE.

Application filed January 2, 1924. Serial No. 683,847.

To all whom it may concern:

Be it known that I, MARK SPRENKLE, a citizen of the United States, residing at Bridgeton, in the county of Cumberland and 5 State of New Jersey, have invented certain new and useful Improvements in Bevel Squares, of which the following is a specification.

My invention relates to bevel squares and 10 its objects are to provide a bevel square of simple and durable construction which may be quickly adjusted into various angular positions, and which will positively hold the adjustment during rough use.

15 These objects, and other advantageous ends which will be described hereinafter, I attain in the following manner, reference being had to the accompanying drawings in which.

20 Figure 1 is a side elevation of a bevel square constructed in accordance with my invention,

Figure 2 an inverted face view of a blade which forms a part of my invention,

25 Figure 3 a section on line 3—3 of Figure 1,

Figure 4 an end view of Figure 1,

Figure 5 a section on line 5—5 of Figure 3,

30 Figure 6 an edge view of a modified head which forms a part of my invention, and

Figure 7 a side view of another modified plunger which forms a part of my invention.

35 Referring to the drawings, 1 indicates a head having a slit 2 in one end. This slit is preferably in the lateral center of the head and has a blade 3 pivoted therein by a screw 4. The blade may have any desired graduations thereon and its end 5 is preferably beveled. A slide 6, integral with the blade and of arcuate shape, is adjustable in a slotted guideway 7, in the other end of the head. Slide 6 is provided with notches

40 8, preferably curved, on one of its edges and its other edge 9 engages the inner surface 10 of the slotted guideway 7. A plunger 11, slidable in the head, passes through the guideway and extends above the slide toward the blade. A shoulder 12, preferably curved, is provided near the lower end of the plunger and is adapted to engage the notches to hold the slide in an adjusted position. The notches may be located at different points on the slide to give

any desired angular adjustment of the blade. As shown these notches are located to give $\frac{1}{2}$, $\frac{1}{3}$, $\frac{1}{4}$ and $\frac{1}{6}$ pitch and are marked 45° , 30° , $22\frac{1}{2}^\circ$ and 15° respectively. The notch, not marked, is used for locking the slide to the head when the blade is at 90° thereto. The plunger may be held within the notches, to keep the edge 9 in engagement with the surface 10, by any suitable means preferably by a threaded upper end 13 in the plunger 65 having a nut 14 screwed thereon and engaging the head.

To quickly adjust the blade, when nut 14 is loosened, a spring 15 is interposed between the nut and head to hold the plunger 70 against the notched edge of the slide. As the blade reaches the proper angle, a click from the plunger will be felt which indicates that the proper notch is in registry. The curved contour of the notches and of 75 shoulder 12, allow an easy sliding movement of the notches over the shoulder.

In Figure 6, I have shown a guideway 7^a which is slotted instead of slotted. In all other respects the construction of the head 80 is similar to that shown in Figure 1.

In Figure 7, I have shown a plunger 11^a provided with a lip 16 extending from shoulder 12^a to provide a slot 17 through which the slide may pass.

85 To adjust the blade of my beveled square into an angular position relatively to the position shown, the nut 14 is loosened until a downward sliding movement of the plunger frees shoulder 12 from notch 8. Spring 15 will normally keep shoulder 12 in engagement with the notch and slide. The blade is then moved until the proper notch for the required angle or pitch is in registry with shoulder 12. This position of the notch is readily ascertained by a click which is felt from shoulder 12 engaging the notch by reason of spring 15. Nut 14 is then tightened to secure the plunger to the head and the square is ready for use. 100

By constructing a beveled square as above set forth the slotted ends may be readily milled and the blade easily stamped from sheet metal. The blade and head are easily assembled and a durable and efficient tool 105 provided. By locating the means, for holding the slide in adjusted position, on the head between the blade and slide, said means will be protected from accidental knocks which are likely to loosen them and 110 disturb the adjustment of the blade.

While I have described my invention as

taking a particular form, it will be understood that the various parts may be changed without departing from the spirit thereof, and hence I do not limit myself to the precise construction set forth, but consider that I am at liberty to make such changes and alterations as fairly come within the scope of the appended claims.

Having thus described my invention, 10 what I claim as new and desire to secure by Letters Patent is:—

1. A bevel square including a head having a slit in one end; a blade pivoted to the other end; an arcuate slide on the blade 15 adjustable in the slit; a plunger slidable in said head and engaging the slide for keeping it in adjusted position; means for securing the plunger in such adjusted position; and resilient means for automatically 20 drawing the plunger against the slide.

2. A bevel square including a head having a slit in one end; a graduated blade pivoted to the other end; a segmental slide integral with the blade and having one edge 25 notched; a plunger slidable in the head adapted to engage the notches and hold the slide against movement; and means for automatically 30 drawing the plunger into said notches.

3. A bevel square including a head having a slit in one end; a blade pivoted to the other end; an arcuate slide on the blade having one edge provided with notches and the other edge engaging the inner surface

of the slit; a plunger slidable in the head 35 and having a shoulder adapted to engage the notches and hold the slide against the inner surface, and means for automatically drawing the plunger so as to bring its shoulder into said notches and the slide to- 40 ward said inner surface.

4. A bevel square including a head having a slit in one end; a blade pivoted to the other end; an arcuate slide integral with 45 said blade and having one edge notched; a plunger slidable in the head and having a shoulder adapted to engage the notches and hold the blade against movement, a nut on the plunger for actuating the same to bring its shoulder within the notches; and means 50 for automatically drawing the plunger so as to bring its shoulder into said notches.

5. A bevel square including a head having a slit in one end; an arcuate blade pivoted to the other end; a slide integral with 55 said blade and having one edge notched and the other edge engaging the inner surface of the slit; a plunger slidable in the head and having a shoulder adapted to engage the notches and hold the slide against 60 the inner surface; a nut on the plunger for securing it to the head, and resilient means between the nut and head for keeping the plunger in engagement with the slide when the nut is disengaged from the head. 65

In testimony whereof I have signed my name to this specification.

MARK SPRENKLE.
